UNITED STATES PATENT OFFICE.

JOHN B. BARTHOLOMEW, OF PEORIA, ILLINOIS, ASSIGNOR TO AVERY MANUFACTURING COMPANY, OF PEORIA, ILLINOIS.

CULTIVATOR.

SPECIFICATION forming part of Letters Patent No. 701,003, dated May 27, 1902.

Application filed June 6, 1896. Serial No. 594,580. (No model.)

To all whom it may concern:

Be it known that I, JOHN B. BARTHOLOMEW, a citizen of the United States, residing at Peoria, in the county of Peoria and State of Illinois, have invented certain new and useful Improvements in Cultivators; and I do declare the following to be a full, clear, and exact description of the invention, such as will enable others skilled in the art to which it applies to make and use the same, reference being had to the accompanying drawings, and to the letters of reference marked thereon, which form a part of this specification.

Figure 1 is a perspective of a cultivator embodying my improvements. Fig. 2 is a side elevation. Figs. 3 to 8 are perspectives of details. Fig. 9 is a side view of the beam holding and lifting devices.

In the drawings, A A indicate the ground-wheels; B, the crank-axle; C, the tongue; D D, the longitudinal frame-bars, and D' the seat. These may be of any well-known or of any preferred form.

E E indicate the beams or drag-bars, to which are attached the standards or shanks for the shovels. They are pivotally connected with the frame, preferably by means of clips G, secured to the downward and inward turned parts f of the cross-bar at F. The forward pivots of the beams or drag-bars are shown at e. The beams are supported, lifted, and lowered in the following manner:

H is a bar or radius-arm supported upon and extending upwardly from the transverse part of the crank-axle B. Preferably this bar H is pivoted to the ears i on a plate I, which is clamped to said axle B, as shown in Fig. 9. The bar H is formed with a hook or projection h at the upper end and an arm or extension h' at its lower end, each for a purpose to be described.

J is a bar or suspension-rod pivotally connected to a beam or drag-bar E and extending up to the upper end of the bar H. Preferably it is formed of a tube or pipe clamped at its lower end in the bifurcated support J', which is secured to the pivot-plate J², and at the upper end is provided with a ferrule having a projection formed with a hook j and an aperture j², said parts constituting a forward curved terminal for the suspension-rod. The

hook or finger h of the aforesaid bar H is inserted in the aperture j², whereby a flexible but sufficiently firm connection between the parts H and J is provided, and at the same time they are allowed to be quickly separated without requiring the removal of bolts or pins.

The bars H and J are provided with a stop or regulator to limit their backward movements. As shown, this consists of a chain K, and in order to provide resiliency the chain is attached to a spring k. The regulator-spring is secured to the cross-bar F of the main frame, and the upper end of the chain is engaged with the aforesaid hook j on the bar J. By employing a chain like that at K I can apply the regulator or stop to the best advantage with respect to the leverage of the bar H and at the same time avoid the presence of a long stop-bar, such as would be necessary to extend to the upper end of the part H. A stop is also provided to limit the forward movement of the bar J and the bar H. As shown the axle or parts attached thereto furnish such stop, as shown in Figs. 1 and 9. Each of the beams is provided with a set of parts such as described.

By examining the drawings it will be seen that the several movable parts are so arranged that when it is desired to elevate the beams or drag-bars at their rear ends it can be done by lifting on the bars J and pressing them forward. Such action throws forward also the bars H, and when the beams are in their uppermost position the bars J are inclined forward on such a line that they lie very nearly in the transverse plane of the pivot of the bottom hinge of the bars H—in other words, they are very nearly held by a toggle-lock.

To assist in moving and holding the beams and the above-described parts, I combine therewith the following:

L indicates as a whole a spring device which is pivotally connected to the bar H near the pivot at its lower end, it comprising the spring proper, l, and the notched adjusting-bar l'. The spring is at its front end connected to a suitable holder, so that it will be adapted to tend to draw forward on the bar H and assist in counterbalancing and lifting the beam.

M is a bar which at one end is pivoted to the aforesaid extension h' on the bar H and at the other end is formed with the hook m , to which is attached the spring l . This bar 5 M can move longitudinally, it having a guide on the main frame at m' .

By examining Fig. 9 it will be seen that when the parts are in their working positions the force of the spring l is neutralized because of the fact that the bar M is bearing against the extension h' in, or nearly in, the line of the axis at i , around which the bar H rotates, and it will be also seen that as soon as the pivot-point at h^2 gets below the 15 said line (as it does the instant after a slight lifting pull is exerted in the bar J) the spring l acts in a twofold way to draw forward the bar H and to therefore lift up the bar J and its beam, one element of its action being a 20 forward pull from the spring itself and the other element being a pressure or push below the axis at i , resulting from the fact that the bar M is pushed endwise through its 25 guide m' by the draft exerted by the forward end of the spring l . Thus a powerful lifting force can be brought to bear with a spring having at its end only one-half the travel that would be necessary if its forward end were 30 fixed in relation to the main frame. This 35 twofold or double action of the lifting-spring is not necessarily dependent upon the particular arrangement and location of the spring and the parts which are intermediate 40 the spring and the beam (shown in the drawings) in order to effect the advantages just described. To secure these advantages, it is only necessary that the spring should have 45 a movable support or attachment for each end and that such supports or attachments should be connected with the beam with more or less directness, so that the force of the spring shall be transmitted through both its supports or attachments to the beam with a lifting effect from each. The movements 50 referred to in speaking of the supports or attachments for the spring are movements relative to the main frame of the cultivator, which may be considered as being stationary so far as movements of parts which effect 55 the lifting of the beams are concerned. The spring-lifter at L is arranged along and acts on approximately horizontal lines. By thrusting against the handle j' on the bar or suspension-rod J the bar or radius-arm H 60 swings forward about its pivot at i , and thus through the suspension-rod J raises the particular gang-beam to riding position. As approach is made to such position the pivotal or loose connection at h at the free end of the 65 bar or radius-arm H moves toward the line connecting the pivot at i with that at J^2 . By proper adjustment the spring-lifter L remains in play until the final position of rest is reached in the forward movement of the bar or radius-arm H. The advance of the radius-arm toward 70 its final position constantly lessens the tension of the spring-lifter. This loss is cor-

rected by reason of the direction of the pull and the point of attachment for the spring-lifter to the radius-arm. Being applied near 70 the pivot of the arm, the short leverage of the lifter is exerted at best advantage during the traverse of the radius-arm past the vertical. Hence the counterbalancing effect of the 75 spring-lifter remains practically uniform throughout the shift. On the contrary, if the shovels are forced into the soil from the position shown by Fig. 2 it is the spring stop or regulator H which comes more and more in play. As the beam is lowered the regulator 80 K, with its long leverage upon radius-arm H at the hook j , exerts an increasing power, whereas the lifter L, although distended proportionately, exerts its force with lessening effect. The radius-arm is receding from the 85 vertical, so that the attachment of the lifter at short leverage tends constantly to minimize its pulling action.

What I claim is—

1. The combination of the main frame, the 90 vertically-swinging plow-beams, the radius-bars pivoted to the main frame, the suspension-bars pivoted to the beams at points relatively near their rear ends, hinge-like devices for connecting the suspension-bars to the radius-arms, and the lifting-springs each exerting a lifting force upon one of the radius-arms by pulling upon one side of its pivot-axis and by pushing upon the other side, substantially 95 as set forth.

2. The combination of the main frame, the vertically-swinging plow-beams, the radius arms or bars, H, extending upward from and pivoted to the main frame, the suspension-bars J pivoted to the beams at points relatively near their rear ends and detachably connected by hinge-like devices to the upper ends of the radius-bars, the yielding regulators, K, to govern the backward movement of the bars H and J, the lifting-springs, L, pulling forward on the bars or arms H, above their pivots, and the bars, M, connected to the springs L and bearing backward on the radius-arms below their pivots, substantially as set forth.

3. The combination of the main frame, the vertically-swinging plow-beam pivotally supported at its front end, the lifting-spring mechanism L, the radius-arm H hinged to and projecting upward from the main frame and connected to one end of the spring mechanism, L, the bar M connected at one end to the spring mechanism and at the other end to the arm H, and the suspension-bar J pivoted to the beam at a point in the rear of the front beam-pivot and extending upwardly therefrom and flexibly connected to the radius-arm H above the main frame, substantially as set forth.

4. The combination of the main frame, the 130 vertically-swinging plow-beam pivotally supported at its front end, the suspension-bar J pivoted to the plow-beam at a point in rear of the front beam-pivot and extending to a point

above the main frame and adapted to swing forward, a stop to limit the forward motion of said bar J, a lifting-spring arranged to draw forward the bar J, means for connecting said spring with said bar, and the movable bar M connected with the spring and aiding to move the bar J in said forward direction, substantially as set forth.

5. The combination of the main frame, the vertically-swinging plow-beam pivotally supported at its front end, the suspension-bar, J, pivotally connected to the plow-beam at a point in the rear of the front beam-pivot, the radius-bar, H, pivoted to the main frame and 15 flexibly connected above said frame to the bar J, said bars, H and J, being adapted to be inclined forward and to lie in approximately coincident planes, a stop limiting the movement of said bars, and a spring lifting mechanism connected to said bars substantially as described and comprising means for exerting force both forward and backward relatively to the main frame to effect the lifting, substantially as set forth.

25 6. In a cultivator, the combination of the beam, a radius-bar from which the beam is suspended, arranged to incline, from the vertical, toward the rear when the beam is in working position, and an approximately horizontal double-acting lifting spring mechanism connected at one end to the radius-bar near its fulcrum, whereby the efficiency of the spring increases, as to the direction in which its force is applied, during the first 30 part of the lifting of the beam, substantially as set forth.

7. In a cultivator, the combination with the main frame, of the vertically - adjustable beam, the radius-arm, the suspension-rod connecting the beam and the radius-arm, and a double-acting lifting spring mechanism connected at one end with the radius-arm near its fulcrum, such connection moving away from a line which would include the fulcrum 45 of the radius-arm and the other end of the spring, as the radius-arm is moved to lift the beam, substantially as set forth.

8. In a cultivator, the combination of the vertically - adjustable beam pivotally suspended at its forward end, a radius-arm, a suspension-rod connecting the beam and the radius-arm and a double-acting spring mechanism having a coiled lifting-spring connected at one end to the radius-bar, the relative 50 position of the radius-bar and the spring being such that the efficiency of the spring, as to the direction in which its force is applied to the radius-bar, rapidly increases during the first part of the lifting operation, substantially as set forth.

9. The combination with a machine-frame, of a plow-beam, a suspension-bar extending upwardly therefrom, a rocking lifting-lever pivoted upon the machine-frame and connected with the suspension-bar, a beam-lifting spring, and means whereby said spring acts upon said lever at two different points

and in substantially opposite directions to rock the same and lift the beam.

10. In a cultivator of the hammock type, 70 the combination of the main frame, the plow-beam adjustable vertically and adapted to swing laterally at its rear end, the radius-bar or lever having a fulcrum on said frame and extending upward therefrom, means for suspending the beam from the upper part of said bar, a pulling member connected with said bar, and a pushing member connected with said bar, said members acting to give the beam an upward movement, and one of said members being a spring adapted to actuate the other member.

11. In a cultivator of the hammock type, the combination of the main frame, the plow-beam connected with said frame to be adjustable vertically and swinging laterally, a radius-arm mounted on a fulcrum on said frame and extending upward therefrom to a relatively high point above said beam, means for connecting the beam and the upper part of 85 said radius-arm, and two springs connected directly to, and above the fulcrum of, said radius-arm at different heights, the two lines of draft of said springs inclining toward each other and toward a point forward of the lower 90 part of said radius-arm.

12. In a cultivator of the hammock type, the combination of the main frame, and axle, the plow-beam connected with said frame to be adjustable vertically and swinging laterally, a radius-arm mounted on a fulcrum on said frame and extending upward therefrom to a point relatively high above said beam, suspension means connecting the beam with the upper part of the radius-arm, said suspension means being at the rear of the axle and movable laterally at their lower ends, an approximately horizontal beam-lifting spring connected with said radius-arm at a point near the fulcrum thereof, and a second and regulating spring acting on the beam when in the working position.

13. In a cultivator of the hammock type the combination of the main frame and the axle B, the plow-beam connected with said frame to be adjustable upward and downward and swinging laterally, a radius-arm mounted on a fulcrum on said frame extending upward therefrom to a relatively high point above said beam, and movable forward from 115 a position in rear of said fulcrum as the beam is lifted, means at the rear of said axle for connecting the beam and the upper part of said radius-arm, and a substantially horizontal spring having a connection with said radius-arm near its fulcrum to force the arm forward.

14. In a cultivator of the class described, the combination with the beam thereof, of the radius-arm, the lifting-spring arranged substantially horizontally and connected to the 120 radius-arm near the fulcrum thereof, a second spring for regulating the shovels when at work, and means for throwing the regulating-spring entirely out of action after the beam

commences to rise toward its uppermost position, substantially as set forth.

15. In a cultivator of the class described, the combination of the beam, the radius-arm, 5 the regulator-spring adapted to act upon the beam when in its working position, a lifting-spring, and devices connecting one end of the lifting-spring with the radius-arm, the connection of such devices with the radius-arm being movable to and away from a line which 10 includes the fulcrum of the radius-arm and the end of the spring to which said connecting devices are united, substantially as set forth.

16. In a cultivator of the class described, 15 the combination with the frame and beam thereof, of beam-suspending devices mounted by a suitable fulcrum on said frame, a lifting-spring connected to said suspending devices, 20 and adapted to vibrate to and from a line which is radial to the fulcrum of the suspending devices and includes the outer end of the spring, a second spring connected to said suspending devices, and adapted to regulate the 25 shovels when in their working position, and means for throwing said second spring out of operation when the beam is lifted, substantially as set forth.

17. In a cultivator of the class described, 30 the combination with the beam thereof and suspension-bar, of a radius-arm having two members projecting in different directions from its axis, a regulator-spring controlling the 35 positions of the shovels when at work and connected to one of the said members of the radius-arm, and a lifting-spring connected with the other member of said radius-arm, substantially as set forth.

18. In a cultivator of the class described, 40 the combination with the beam thereof, of a radius-arm connected with the beam, a suspending rod for the beam, a spring, means for connecting the spring to the radius-arm on one side of its axis, means for connecting said 45 spring to the radius-arm on the other side of its axis, whereby the spring can both push and pull around said axis, and a second spring connected to the beam-suspending devices and adapted to control the shovels when in 50 working position, substantially as set forth.

19. The combination of the main frame, the plow-beam vertically adjustable relative to the frame, the radius-arm pivotally connected to the main frame and extending upward 55 therefrom, means for suspending the beam from the said radius-arm, the arm h' connected to the radius-arm, the sliding bar pivoted to the arm h' and adapted to press backward substantially on the line of the pivot of the 60 radius-arm, and also below it, and the spring connected at one end to the sliding bar, and at the other end connected with the radius-bar, substantially as set forth.

20. In a cultivator of the class described, 65 the combination of the beam-suspending rod, the radius-arm on the frame having a connection with said rod and an arm or extension

extending below its fulcrum, the beam lifting or elevating spring, and means for imparting pressure from the spring to the said 70 arm or extension below the fulcrum to move the upper end of the radius-arm forward, substantially as set forth.

21. In a cultivator of the class described the combination with the beam pivotally supported 75 at its front end, of a radius-arm, a beam-suspending rod pivoted to the beam at a point behind its front pivot and connected with the radius-arm, a lifting-spring, a pulling connection or attachment between one end of the 80 spring and the radius-arm on one side of its fulcrum, and a pushing connection or attachment between the spring and the radius-arm and arranged to push on a line on the other side of the fulcrum from that on which the 85 pulling connection operates, substantially as set forth.

22. In a cultivator, the combination, with the frame, of a beam pivotally supported near its front end, a radius-arm, a suspension-bar 90 connecting the upper end of the radius-arm and the beam at a point in rear of the front beam-pivot, the radius-arm and suspension-bar being arranged to swing, whereby the beam is adjusted vertically, and a lifting-spring having at each end movable connecting means with the beam, whereby the force of the spring is applied from both its ends during the lifting operation, substantially as 95 and for the purposes set forth.

23. The combination of the frame, the beam pivotally supported at its front end and vertically adjustable relative to the frame, a double-acting spring-lift mechanism for the beam, a movable support or attachment for one end 105 of the spring, means connecting said support or attachment with the rear part of the beam, a movable support or attachment for the other end of the spring, and means for connecting the last said support or attachment also with the rear part of the beam at points behind the front beam-pivot, whereby the elastic force at each end of the spring is brought to bear upon the rear part of the beam, substantially as set forth.

24. The combination of the main frame, the vertically-adjustable beam, the coupling interposed between the front end of the beam and the frame, a double-acting spring lifting mechanism connected with the rear end of 120 the beam, and comprising a spring, a movable support or attachment for one end of the spring, and a movable support or attachment for the other end of the spring, a radius bar or arm pivoted to the main frame, means connecting the two movable spring supports or attachments to the radius-arm substantially as described, whereby the force of the spring as applied to the radius-arm through both of 125 said supports or attachments tends to move it in one direction, and means independent of the said coupling for connecting the radius-arm to the cultivator-beam at a point in the rear of the coupling, substantially as set forth.

25. The combination of the main frame, the
cultivator-beam pivotally supported at its
front end, means for suspending the rear end
of the beam whereby it is free to swing lat-
erally, a double-acting spring lifting mech-
anism supported on the main frame and held
against lateral movement, it comprising a
spring and a movable support or attachment
for each end of the spring, both of said sup-
ports being adapted to be moved by the spring,

and means for connecting both of said spring
supports or attachments with the beam at or
near its rear end at points behind the front
beam-pivot, substantially as set forth.

In testimony whereof I affix my signature 15
in presence of two witnesses.

JOHN B. BARTHOLOMEW.
